UNITED STATES PATENT OFFICE.

GEORGE S. CHASE, OF SPRINGFIELD, MASSACHUSETTS.

HEAT-GENERATOR.

SPECIFICATION forming part of Letters Patent No. 703,540, dated July 1, 1902.

Application filed March 22, 1902. Serial No. 99,416. (No model.)

To all whom it may concern:

Be it known that I, GEORGE S. CHASE, a citizen of the United States of America, and a resident of Springfield, in the county of Hampden and State of Massachusetts, have invented certain new and useful Improvements in Heat-Generators, of which the following is a full, clear, and exact description.

This invention has for its object to provide an apparatus by means of which the heat from an ordinary oil-lamp may be economically utilized and conserved for raising the temperature in a room, accomplishing this with the avoidance of smoking or objectionable odor.

The improvements relate to the construction of the heater, to means for its support at any such proper height as to accommodate it to be used in conjunction with a lamp, whether a low or tall lamp, to means whereby the heater may have a swinging movement in an upward direction, so that it may be disengaged from the upper end portion of the chimney of the lamp to permit the removal of the lamp and its chimney away from and without obstruction by the heater, and to means whereby the heater at its lower end opening is adapted to be used in conjunction with the upper end portion of lamp-chimneys of large or small diameters.

The invention consists in the construction of the heater, in combination therewith of supporting and adjusting appliances, all substantially as hereinafter fully described, and set forth in the claims.

Reference is to be had to the accompanying drawings, in which—

Figure 1 is a side elevation and central vertical sectional view of the apparatus with an ordinary lamp indicated as having its location for utilization in conjunction with the heater. Fig. 2 is a plan view of the heater apparatus. Fig. 3 is a plan view of an internal part of the heater inverted. Fig. 4 is an inverted plan view of an appliance for contracting a circular lower end opening of the heater, and Fig. 5 is a sectional view showing the latter as in its connection at the bottom of the heater.

Similar characters of reference indicate corresponding parts in all of the views.

In the drawings, A represents the heater,

consisting of upper and lower separated circular chambers *a* and *b*, the walls of which may be advantageously composed of sheet metal. The lower chamber has the central depending annular wall *d*, surrounding the lower circular opening *f*, leading into the lower heater-chamber *b*, and the upper chamber *a* has the central upwardly-leading chimney *g*. The upper and lower chambers are connected by the vertical circular flues *h h*, which extend through the separating-space *i* between the two chambers, as shown.

B represents a heat concentrating and arresting device, the same being in the form of an inverted-cup-shaped part supported by the pin or rivet *j* from and slightly below the top wall of the lower chamber *b*, the washer *m* serving to hold the parts so that the separating-space *n* is created.

C represents a post or standard rising above a suitable base *D*, the same being screw-threaded, as indicated at *o*, and loosely receiving the sleeve-like part *q*, having the lateral extension *r*. The nut *s*, screw engaging the post *o*, constitutes an adjustable support for the sleeve-like part *q*.

G represents a part of the apparatus, which comprises the two parallel arms *t t* and the uniting member *t²*, which has the median projection *t³*, which is so hinge-connected at *t⁴* with the member *r* of the sleeve *q* as to be capable of having the rigidly-supported horizontal disposition, as shown in Fig. 1, and to be swung in an upward direction therefrom, so as to carry the depending annular portion *d* of the heater upwardly out of engagement with the upper end portion of the chimney *x* of the lamp to permit the lamp to be taken away, and this arrangement of course facilitates the quick and easy bringing of the lamp into the position shown of connection with the heater.

The engagement which the heater has with the supporting horizontal parallel members *t t* is by means of the sheet-metal loops or straps *u u*, provided upon the top wall of the upper chamber *a* of the heater, or by the similar straps *u² u²*, provided at and depending below the lower wall of the lower chamber *b*.

In the illustration shown the lamp may be considered as a comparatively low lamp, and therefore the heater has its support by the

upper straps u u , depending below the arms t t of the swinging heater-support G ; but in case a considerably-higher lamp were to be employed or one having a higher chimney 5 the heater A could readily be slid off from the strap connections, with the arms t t and the heater carried above the heater-support, the engagement being now made by sliding the lower straps u^2 u^2 about and along the 10 arms t t .

Now in order that the best conditions for heating may be acquired the heater may be further slightly vertically adjusted either to place it higher or lower, which may be done 15 by changing the position of the nut s in its screw engagement on the post, the sleeve q being correspondingly raised or lowered.

The aforementioned heat-concentrating appliance B may comprise internal baffle walls 20 or partitions, which may be concentric with each other, as indicated at v v , leaving downwardly-opening annular spaces, or such plates may be parallel or otherwise disposed with relation to each other, the object thereof being 25 to arrest and retain the heat from the lamp within the lower chamber a sufficiently long to acquire the satisfactory proportion of its radiating effect thereat before the similar radiating effect by such heat from the lamp 30 is acquired in and about the upper heater-chamber.

The apparatus is equipped with an appliance whereby the lower opening f , leading upwardly thereinto, which is comparatively large 35 for the reception therein of a correspondingly large upper-ended lamp-chimney, may be contracted to adapt the heater for the combination therewith of a lamp having a chimney with a considerably-smaller upper end 40 portion, and it will be perceived that a sleeve-like part w is provided, having at its lower end a horizontally-turned internal flange w^2 , and said sleeve has the radial studs w^3 for engagement by bayonet-joint connection with 45 the angular slots y to the opposite sides of the depending wall d .

Having thus described my invention, what I claim, and desire to secure by Letters Patent, is—

50 1. A heater of the character described, consisting of upper and lower separated chambers having vertical connecting-flues, the upper chamber having an upwardly-leading opening, and the lower chamber having a downwardly-leading opening, and a support comprising an upright and a laterally-extending part on which the heater is sustained.

2. A heating apparatus of the character described, consisting of a heating-chamber, having 55 upper and lower openings and having its top and bottom walls provided with the straps u u and u^2 u^2 , combined with the support con-

sisting of an upright member and a part G horizontally sustained thereby, comprising the two separated parallel horizontal members 60 t t , to engagement with which either the upper or the lower pairs of said straps may be brought, for the purpose set forth.

3. In a heating apparatus of the character described, the combination with a base, an upright, and a part vertically adjustable on the upright, of a part G comprising separated members t t , hinge-connected to the part q , and a heater supported by the members t t , and having a heating-chamber provided with 75 the bottom opening leading thereinto, and one or more openings leading upwardly therefrom.

4. In a heating apparatus of the character described, a heater comprising upper and 80 lower separated heating-chambers a and b , the former having an upwardly-leading opening at its top, and the latter having a central opening at its bottom, and said chambers being connected by the vertical flues h h , and 85 the lower chamber having therewithin and supported slightly below, its top wall, with a space intervening, a depending cup-shaped part having therewithin a plurality of partitions to separate downwardly-opening spaces, 90 and means for supporting the so-constructed heater in an elevated position.

5. In a heating apparatus of the character described, the heater comprising the upper and lower separated chambers a and b , and 95 the connecting vertical flues, the upper chamber having a top opening g , and the lower chamber having the depending annular wall with the opposite angular slots y , the contracting appliance consisting of an annular 100 part having the radial studs w^3 , and having the internal flange portion w^2 , and means for supporting the heater in an elevated position.

6. In a heating apparatus of the character described, in combination, the base D , the uprights C which are screw-threaded, the nut s thereon, the sleeve part q , having the lateral projection r , the part G comprising the portion t^3 hinge-connected to the part r , and the pair of separated parallel arms t t , the upper 105 and lower heating-chambers a and b , the connecting-flues h and said chambers having the openings g and d , and provided with the loop-straps u u , and u^2 u^2 , and the lower heater-chamber having therewithin the inverted-cup-shaped heat-arresting device, substantially as described.

Signed by me at Springfield, Massachusetts, in the presence of two subscribing witnesses.

GEORGE S. CHASE.
